DESIGN FOR AN AIR CONDITIONING CONTROL

Chester A. Rudolph, Minneapolis, Minn.

Application July 26, 1940, Serial No. 93,955

Term of patent 14 years

To all whom it may concern:

Be it known that I, Chester A. Rudolph, a citizen of the United States, residing at Minneapolis, in the county of Hennepin and State of Minnesota, have invented a new, original, and ornamental Design for an Air Conditioning Control, of which the following is a specification, reference being had to the accompanying drawing, forming part thereof, and in which

Figure 1 is a perspective view of an air conditioning control embodying my new design looking from a point above and to the left; and

Figure 2 is a perspective view of the same looking from a point below and to the right.

I claim:

The ornamental design for an air conditioning control, substantially as shown.

CHESTER A. RUDOLPH.
